ALLAN RAMSAY, OF FOLKESTONE, ENGLAND.

MECHANISM FOR PRODUCING GAS-LIGHTED FLASH-SIGNS AND THE LIKE FOR
ADVERTISING PURPOSES.

1,069,702.

Specification of Letters Patent. Patented Aug. 12, 1913.

Application filed September 7, 1912. Serial No. 719,043.

To all whom it may concern:

Be it known that I, THOMAS JACKSON, a subject of the King of Great Britain and Ireland, residing at 7 Milton Court road, 5 New Cross, London, S. E., England, have invented new and useful Improvements in and Relating to Mechanism for Producing Gas-Lighted Flash-Signs and the Like for Advertising Purposes, of which the following is a specification.

This invention relates to mechanism for producing gas lighted flash signs and the like for advertising purposes of the type in which an expanding and contracting chamber 15 operates a tilting device having a gravity controlled element for operating the control valve, and has for its object the improved arrangement and construction of a self contained apparatus of a simple form 20 which is adapted to operate by the gas pressure itself in a reliable manner.

This invention consists in the arrangement of a tiltable control valve such for example as that described in United States Letters Patent 1,042,117, dated October 22, 25 1912, in a fixed manner upon the movable wall of an expandible chamber adapted to take positions of varying angularity during the motion of expansion and contraction of 30 said chamber produced by its periodic inflation with the illuminating gas, and means by which the moving connections between the gas supply, the burner supply and the expandible chamber are effected within the 35 said chamber itself.

In order that the invention may be the better understood, I will now proceed to describe the same in relation to the accompanying drawings, reference being had to 40 the letters and figures marked thereon.

Like letters refer to like parts in the various figures in which:—

Figure 1 is a sectional view of a gas pedestal lamp with my invention installed 45 in the base thereof. Fig. 2 is a full size plan of the valve seat in a modified form to serve two lamps. Fig. 3 is a sectional elevation of the same.

To carry the invention into effect within 50 a suitable casing or upon a suitable stand or frame *a* I fixedly mount an expandible chamber *b* such as a bellows having a wall *c* adapted to oscillate through a given angle and upon the wall *c* I mount the tiltable

control device *d*. This device is provided 55 with three sets of orifices or ports *e f* and *g* communicating with the interior of the chamber *b*, *f* for connection to the gas supply *h* and *g* for connection to the burner *i*. The orifice *e* for the chamber *b* opens directly thereinto, while the two orifices *f* and *g* are connected to flexible pipes *j* and *k* leading through the fixed wall *l* of the chamber *b* communicating with the gas supply *h* and burner *i* respectively, or other 60 movable devices adapted to form a continuous means of communication between a fixed device and a moving device may be used. The orifices *f* and *g* are controlled by a double 65 tilting valve *m* on the top of which a ball *n* is 70 adapted to roll to tilt the valve *m* from part of the seating to the other. I prefer to mount the gas standard *o* upon the upper part of the casing or frame *a* immediately 75 over the expandible chamber *b* so that it forms a substantial and convenient pedestal for supporting the gas standard *o*.

It will be seen that directly the gas is turned on at the supply *h* the chamber *b* alternately expands and contracts under 80 the action of gas supply and delivery respectively and in so doing tilts the tiltable device *d* from one side to another so that the weight of the ball *n* under the action of gravity is utilized to work the control 85 valve *m* about its knife edge *p* to effect the alternate action automatically.

In Figs. 2 and 3 I have provided an additional orifice *g'* which can be connected with a second burner to obtain a duplicate 90 effect of an alternating character, such as might be required for a two color sign.

Having thus fully described my invention I claim as new and desire to secure by Letters Patent:—

1. A gas flash lighting apparatus comprising an expandible chamber having a movable part adapted to move through a curvilinear path, so as to take up positions of varying angularity, a gravity controlled 100 valve arrangement directly mounted in a rigid manner on the said movable part and means contained within the said chamber for connecting the gas supply and the lighting burner with the said valve arrangement 105 whereby the said valve arrangement will automatically control the admission and delivery of the gas when the said chamber

expands and contracts, substantially as described.

2. A gas flash lighting apparatus comprising an expansible chamber having a fixed part and having a movable part adapted to move through a curvilinear path, so as to take up positions of varying angularity, a gravity controlled valve arrangement directly mounted in a rigid manner on 10 the said movable part and flexible communicating means disposed within the chamber connecting the valve orifices of the valve

arrangement with supply and delivery pipes mounted in the wall of the fixed part of the expansible chamber, substantially as 15 described.

In testimony whereof I have signed my name to this specification in the presence of two subscribing witnesses.

THOMAS JACKSON.
